CLAIM

The ornamental design for a temple arm ear piece for eyewear, as shown and described.

DESCRIPTION

FIG. 1 is a front perspective view of the temple arm ear pieces for eyewear of the present application;

FIG. 2 is a front elevation view thereof;

FIG. 3 is a rear elevation view thereof;

FIG. 4 is a right elevation view thereof;

FIG. 5 is a left elevation view thereof;

FIG. 6 is a top elevation view thereof; and,

FIG. 7 is a bottom elevation view thereof.

Phantom lining, where used, is for illustrative purposes only and is not intended to limit the claimed design to the features shown in phantom.
